UMBRELLA STRUCTURE

Kenneth T. Norris and Homer E. Rathbun, Los Angeles, Calif.; said Rathbun assignor to said Norris

Application July 9, 1932, Serial No. 621,549

12 Claims. (Cl. 135—22)

This invention relates to umbrella structures and particularly to a type of umbrella structure or frame of large size, and used principally on lawns, beaches, etc., as sun shades.

The object of this invention is:

To provide a collapsible frame including bows and braces hingedly connected together and connected with the usual top notch at the end of a pole, and with a runner slideable on the pole, and to limit the inward movement of the bows and braces when the frame is collapsed, so as to prevent the toggles formed by the bows and braces from settling inwardly against the pole at or over dead center positions.

Still other objects may appear as the description progresses. In the accompanying drawing we have shown a preferred form of umbrella structure embodying our improvements, in which

Fig. 1 is a top plan view of an assembled umbrella frame partially open with the cover removed.

Fig. 2 is a side elevation of the umbrella frame with the cover removed, broken away at points.

Fig. 3 is an enlarged sectional elevation of a suitable top notch.

Figs. 4 and 5 are, respectively, transverse sections of a suitable geat on lines 4—4 and 5—5 respectively of Fig. 2.

Fig. 6 is a sectional plan of the frame on line 30 6—6 of Fig. 2.

Fig. 7 is a fragmentary elevation of the sliding sleeve or runner and pole shown in Fig. 2 with the braces attachable to the bows shown hingedly connected to said sleeve.

Fig. 8 is a perspective view of a typical form of geat embodying our improvements.

Fig. 9 is a perspective view typical of the ends of the braces and the upper ends of the bows showing our improved means for hingedly connecting 40 the bows and braces with the top notch, geats and sliding sleeve.

As is characteristic of umbrellas and frames of this type, the structure shown includes a central pole or shaft 1 with a reduced upper end 2, and provided with an annular shoulder 3 against which shoulder a top notch 4 is held on the upper extremity of the pole. A sliding sleeve or runner 5 is mounted on the lower portion of pole 1 and includes certain improvements of our invention, and has the usual plurality of bows 6, 6 etc. hingedly connected at their upper extremities to the top notch 4 and extending downwardly and outwardly therefrom. A plurality of braces 7, 7 etc., corresponding in number and position to 55 the bows 6, are hingedly connected at their lower

extremities to the sleeve 5 and at their upper extremities to geats 8, 8 etc. respectively, said geats being positioned centrally between the upper and lower extremities of the bows.

Thus as the sleeve 5 is moved upwardly on pole 1 the braces 7 and bows 6 approach horizontal positions until the sleeve reaches a position of rest substantially below the top notch 4.

The top notch 4 and sleeve 5 are substantially the same in form, particularly as to the means of connecting the bows and braces thereto. The top notch is formed of two sheet metal parts including an upper member 9 and a lower member 10. The member 10 has a central opening 11 therein to receive the end 2 of pole 1, and has a flat body portion adapted to rest against the shoulder 3. The members 9 and 10 are formed with peripheral segments 12 and 13 which are separated by radially disposed slots 14, and the segments 12 of the member 10 are bent slightly downwardly and outwardly and thence upwardly at 15, as shown in Fig. 3, to provide seats for hinge pins 16 which are carried in the upper ends of the bows 6.

The upper member 9 of the top notch has a central apertured neck 17 which fits over the end portion 2 of the pole and is curved downwardly and outwardly and is provided on its periphery with the segments 13 and the slits 14 between said segments. It will be noted, however, that the segments 13 are substantially longer in radial directions than the adjacent segments 12 on member 10, and the segments 13 are bent so as to overlie the upwardly turned portions 15 on the member 10, thence downwardly over the outer faces of said portions, and finally inwardly under the segments 12, thereby permanently securing the two members 9 and 10 of the top notch together.

The segments 12 and 13 are so formed as to provide seats or bearings 17' for the pins 16 of the bows 6. The top notch is held against removal from the pole by means of a pin 9' which extends thru the portion 2 of the pole and engages the upper end of neck 17 of member 9.

As shown in Fig. 9 it will be observed that the bows 6 are flattened at their upper ends, as at 18, and the pins 16 are driven into and suitably secured against removal from the portions 18. Said pins are so positioned that the opposite end portions thereof will project outwardly from the opposite sides of the portions 18 for substantial distances. Thus the extended portions of the pins 16 will hingedly seat in the adjacent bearings 17' on opposite sides of each of the slits 14 in the top notch and the flattened portions 18 of the bows 110

will be positioned as shown in the slits 14 so as to permit the swinging of the bows when the frame is collapsed and extended.

The geats 8 are supported on and intermediate 5 the ends of the bows, as shown, and are formed of a single piece of sheet metal so as to provide elongated sleeve portions 19 which tightly fit the bows 6. Said geats are provided with radially disposed flat extensions 20, 20 which are perforated 10 at 21 so as to receive rivets 20', whereby the portions 20 may be held tightly in abutment for immovably clamping the geats on the bows.

Other extensions 22, 22 continue downwardly from the extensions 20 and are spaced apart so as 15 to receive flattened portions 23 at the upper ends of the braces 7 between the extensions 22, 22. Said braces are pivotally attached by means of pins 24 to the extensions 22, 22, and said pins have bearings in perforations 25, 25 formed in the extensions 20, 22.

It will be noted that the extensions 20 and 22 are continuations of each other and that the lines of juncture between the extensions 20 and 22 are inclined downwardly as at 26 so that the spaces 25 27 within which the portions 23 of the braces are positioned are closed at the lines 26. Thus the braces 7, as shown in Fig. 2, will be limited in their swinging movement about their axes 24 as the sleeve 5 is slidably moved upwardly on the pole 1, thereby preventing an over-movement of the braces and the inverting of the umbrella cover and frame.

The portions 23 of the braces correspond to the portions 18 of the bows and the pins 24 are similar to the pins 16 of the bows.

At points slightly below the top notch the frame is provided with suitable means for preventing the complete collapse of the frame inwardly against the pole 1. This may be accomplished 40 in a number of ways, but we prefer as a matter of simplicity and economy to provide semi-circular bends 28 on the bows 6 for said purpose, the bows 6 being bent inwardly as shown so as to engage the pole 1 at points substantially above the geats 45 8. Thus when the frame is collapsed to a maximum extent the pins 24 which hingedly connect the braces 7 with the bows 6 will be disposed outwardly of a vertical line cutting the axes of the pins 16 on the top notch and similar pins 29 on sleeve 5 which serve to hingedly connect the braces 7 with said sleeve. In other words, the bends 28 in the bows prevent the collapse of the frame so that the toggle connections formed by the bows and braces will reach dead center position. Due to this structure, when the pole 1 is held upright with the umbrella and frame downwardly in operative position, the weight of the frame alone is sufficient to cause the complete 55 opening of the umbrella.

The sleeve 5 has an elongated tubular body 30 with a plurality of lugs 31, 31 etc., bent outwardly therefrom in a common horizontal plane to provide seats for a flange 32 which is positioned over the body 30 and rests upon said lugs. A retaining ring 33 is positioned over the upper portion of the body 30 and rests upon the flange 32. Said ring 33 has a tubular neck 34 which extends upwardly over but terminates short of the upper extremity of the body 30 so that when the members 32 and 33 are properly positioned on the body 30 the upper extremity 35 of the body may be rolled outwardly and downwardly over the upper edge of neck 34 so as to permanently lock and hold the members 30, 32 and 33 in telescoping 65 positions.

The members 32 and 33 are provided with superposed segments 36 and 37, respectively, formed thereon and separated by slits, as at 38, as in the case of the top notch 4. The segments 36 of the lower member 32 are bent upwardly and downwardly over the outer edges of the segments 37 reversely of the top notch 4 so as to provide bearings for pins 29 between each pair of segment 36 and 37. The pins 29 are carried in flat portions 38 formed on the lower extremities of braces 7 and said flat portions are hingedly held in the slits 39 between the adjacent pairs of segments. Thus the braces are hingedly connected to sleeve 5 in substantially the same manner as the bows 6 are connected to the top notch 4.

The entire frame is a unitary structure when assembled in the manner shown and described, and the bow and brace structure may be removed as a unit from the pole 1 by detaching the retaining pin 18 from the pole.

The entire structure is simple, economical, rigid and durable.

The provision of means cooperating with or on the bows or pole 1 for limiting the inward swinging of the bows and braces in the direction of the pole so that an angle slightly less than 180° is formed by each of the bow and brace sets when the structure is collapsed with the base line of the angle cutting the pins 16 and 29, one side of the angle cutting pins 16 and 24 and the other side of the angle cutting pins 24 and 29, provides a highly desirable structure, for the reasons stated.

Other advantages will readily appear to those skilled in the art.

What we claim is:

1. In an umbrella structure comprising, a bow attaching member adapted to engage a supporting pole, bows hingedly supported on said attaching member, and means provided on said bows for limiting the movement of said bows toward the pole, when the structure is collapsed, to an extent which will dispose the bows and braces at or beyond dead center positions.
2. An umbrella structure comprising a pole, a frame including bows extensibly mounted relative to the pole, and means on said bows to limit the movement of the bows in the direction of the pole, whereby to prevent the locking of said frame on or beyond dead center positions.
3. An umbrella structure comprising a pole having a top notch fixed thereto, bows pivotally connected to said top notch, said bows having means thereon at corresponding points below said top notch for engagement with a portion of said pole to prevent the disposition of said bows at or beyond dead center positions when the frame is collapsed.
4. An umbrella structure comprising a pole, a frame including a plurality of bows hingedly supported for extension and retraction relative to said pole, and means below said hinged connections for limiting the inward movement of said bows when said frame is collapsed.
5. An umbrella structure comprising a pole, a frame including a plurality of bows hingedly supported on said pole at correspondingly fixed points and adjustably supported at points correspondingly spaced from said fixed points, and means intermediate said fixed and adjustable points of support for limiting the inward movement of the bows when the frame is collapsed.
6. An umbrella structure comprising a pole, a frame including a plurality of bows each extensibly supported at a point spaced longitudinally

of the bow from a fixed point, and means intermediate said points, for limiting the inward movement of the frame when the frame is collapsed.	respective bows intermediate said fixed and adjustable points of support, for limiting the inward movement of the frame when it is collapsed.
7. An umbrella structure comprising a pole, a frame thereon including a plurality of bows hingedly supported for extension and retraction to said pole, and means below said hinged connections and carried by said bows for limiting the inward movement of said frame when the frame is collapsed.	10. In an umbrella frame adapted to be supported on a pole, a plurality of bows having means thereon spaced from the points of support on said pole for engagement with said pole, for preventing the complete collapse of said frame.
8. An umbrella structure comprising a pole, a frame including a plurality of bows each extensibly supported at a longitudinally spaced point from a fixed point of support, and means on each bow intermediate said points of support, for limiting the inward movement of the frame when it is collapsed.	11. In an umbrella structure a frame including a plurality of bows, a supporting member therefor, and means formed on said bows for engaging and limiting the movement of said frame in the direction of said supporting member beyond a predetermined point.
9. An umbrella structure comprising a pole, a frame including a plurality of bows hingedly mounted at their upper ends at correspondingly fixed points and adjustably supported at points substantially remote therefrom, for extending and retracting said frame, and means on said	12. In an umbrella structure a frame including a plurality of bows movably supported for extension and retraction relative to a supporting member, said bows each having a portion bent outwardly from its longitudinal axis for engagement with and for limiting the movement of said bows in the direction of said supporting member.
